MEANS FOR EQUALIZING THE FLOW IN
HEAT EXCHANGE

Harry P. Bowser, Tulsa, Okla.; Helen Bowland Bowser, executrix of Harry P. Bowser, deceased, assignor to H. P. Bowser Manufacturing Company, Tulsa, Okla., a corporation of Oklahoma

Application January 7, 1938, Serial No. 183,897

2 Claims. (Cl. 257—154)

This invention relates to means for equalizing the flow of liquid through a plurality of parallel pipes or ducts and particularly to equalizing the flow through the cooling tubes or pipes of an automobile radiator.

I have found it to be a fact that in no radiators coming under my observation were the cooling tubes efficient. This is for the reason that the only water circulating tubes that were active in these radiators were those nearest the opening leading to the circulation pump and only those tubes were active which were necessary in order to deliver water equal to the capacity of the pump. Thus if the capacity of the pump was twenty gallons per minute, only those tubes necessary to deliver twenty gallons, these tubes being nearest to the suction of the pump, were utilized. This is particularly true of the radiators used in connection with large and powerful internal combustion engines.

The general object of my invention is to provide means whereby all of the tubes or water conveying ducts shall do an equal share of the work or, in other words, that the water shall flow in equal proportions through each tube.

In order to secure this result, I have devised the structure which is illustrated in the accompanying drawings wherein:

Fig. 1 is a vertical sectional view through the radiator of an automobile, the tubes of the radiator being shown in elevation.

Fig. 2 is a vertical medial section through the radiator shown in Fig. 1.

Fig. 3 is a transverse sectional view through the lower portion of a radiator showing a modification of the invention.

Fig. 4 is a transverse section through the structure shown in Fig. 3.

Fig. 5 is a like view to Fig. 4 but showing a modified form of means for supporting the water baffling pan.

In Figs. 1 and 2, I have shown a radiator comprising a tube supporting frame 10, the upper plate 11, and the lower plate 12. Attached to the margin of the upper plate 11 is a header 13 having an inlet 14. Attached to the margin of the lower plate 12 is a lower header 15 having a water outlet 16. Extending through the plates 11 and 12 are a plurality of parallel tubes 17, the upper and lower ends of these tubes extending through the plates 11 and 12 an equal distance, that is, all of the upper ends of the tubes have the same extent above the plate 11 and the lower ends of all of the tubes have the same extent below the plate 12.

Supported above the upper ends of the tubes 17 and within the header 13 is a baffle plate designated 18. This baffle plate at its ends is downwardly flanged, as at 19, this flange extending downward below the upper ends of the tubes 17. Preferably and as illustrated, this baffle plate 18 is supported by screws 20 which extend up through the header 13 and have screw-threaded engagement therewith so that the plate 18 may be raised or lowered. Set nuts 21 hold the plate 18 in any adjusted position. Disposed below the lower ends of the tubes is a baffle plate 22 having upwardly extending marginal flanges 23, these flanges extending above the lower ends of the tubes 17. This baffle plate 22 is also adjustably supported as, for instance, by the screws 24 extending through the header 13 and having screw-threaded engagement therewith and being held by the set nuts 25.

It will be seen that with this construction, the water entering the upper end of the radiator through the pipe 14 flows, as shown by the arrows in Fig. 1, over the plate 18 and down and around the flanged margins of this plate, then upward under the flanges 19 and then down through the pipes. Of course, it is to be understood that the space above the plate will be filled with water and that water will fill the space around the margin of the plate 18 and the space beneath the plate 18, but with this construction, an equalized flow of water to the upper ends of the tubes 17 is produced, so that all of the tubes secure an equal quantity of water and the same is true with regard to the lower end of the radiator. The water flowing out of the tube 17 flows into the pan-like plate or baffle 22, flows upward over the edges of the flanges 23 and then flows into the space below the plate 22 and passes out through the opening 16. Thus an equal depth of water is kept beneath all of the tubes and an equal amount of water flows from each tube. The suction of the pump is thus equalized so that all of the tubes do the same amount of work.

In Fig. 3, I illustrate the lower end of a radiator operating on exactly the same principle as that shown in Fig. 1, but in which the lower plate 12 of the radiator is provided with a downwardly extending apron 26, which is attached to the lower plate 12 exteriorly of the row of tubes 17 and extends down into the pan-like baffle plate 22. In the construction shown in Fig. 3, the baffle plate 22 is supported upon transversely extending brackets 27 in the manner shown in Fig. 4. It is to be understood, however, that this plate 22 might be supported by the screws in the man-

ner previously described and shown in Figs. 1 and 2.

In Fig. 5, I have shown the baffle plate 22 as being supported by brackets 28 extending downward from the plate 12. Otherwise than this, the construction shown in Fig. 5 is precisely the same as in Fig. 4. The upper baffle plate 18 may be supported in the same way.

It is to be particularly noted that in Figs. 3, 10 4 and 5, the lower ends of the tubes 17 terminate in close proximity to the lower face of the plate 12. It is unnecessary to extend the tubes downward into the pan-like baffle plate 22 in this construction because of the skirt or apron 26 which 15 extends down below the marginal flange of the plate 22 and thus forms a trap immersed in the liquid flowing through the tubes and into the lower end of the radiator housing.

It will be noted that in Figs. 3, 4 and 5, the skirt 20 or flange 26 constitutes in effect an extension of the tubes 17, in other words, in place of having each tube extended below or above the edge of flange 23 to compel the water to pass over or under the edge of the flange, the skirt which 25 constitutes an extension of all of the tubes secures the same effect.

In Fig. 4, the plate 22 is shown as attached to the housing 15, which constitutes a header or chamber, hence when this header or chamber 15 30 is removed from the frame 10 which supports the tubes 17, the plate 22 remains attached to the plate 12. In Fig. 4, however, the plate 22 is removable with the header, chamber or housing 15.

While in Fig. 3, I have only illustrated the 35 lower end of the radiator, it is to be understood that the upper end of the radiator is constructed in the same manner with, however, the plate 22 inverted just as the plate 18 is. It is to be understood that the upper end of the radiator 40 might be constructed as shown in Fig. 1, while the lower end of the radiator shown in Fig. 1 might be constructed as shown in Fig. 3. This device regulates or equalizes the flow of a cooling liquid through the multiple tubes of the radiator. The essential feature of this construction 45 is that the radiator housing above the opening of the radiator tubes will constitute a reservoir which will be filled to the same level across the entire top of the radiator before the liquid will 50 flow into any tube, thus causing the liquid to flow equally into all of the tubes at the same time, the same being true of the construction of the lower end of the radiator. The provision of the screws 20 and 24 in Fig. 1 permits the level of the liquid 55 above the tubes or below the tubes to be increased

or decreased, thereby controlling the flow of the liquid going through the radiator in accordance with the necessities of each case.

While I have illustrated my mechanism as applied to the cooling pipes of a radiator, it is to be understood that this idea may be used in connection with means either for heating or cooling liquids and that I do not wish to be limited to the use of this construction in the radiators of internal combustion engines alone. It is possible 10 to use this equalizing device either at the top or bottom of the radiator or at both of these places. It is more efficient, however, when used at the top of the radiator than at the bottom. In any case, it is necessary to form an aperture 15 29 in the top pan to constitute a vent in order to allow free circulation.

What is claimed is:

1. In a heat transfer apparatus of the character described, a plurality of parallel tubes, a header into which the tubes open, the header having a flow opening, the wall of the header through which the tubes project constituting a tube sheet, a skirt secured to the tube sheet and surrounding the area of the sheet through which the tubes open, said skirt extending toward the flow opening, and a baffle plate disposed in said header between the flow opening and the skirt and extending across but in spaced relation to the extremity of the skirt, the plate having a marginal flange 30 surrounding and in spaced relation to the skirt and spaced from the adjacent walls of the header and extending toward the tube sheet to a point beyond the outer edge of said skirt whereby to equalize the flow through all of said tubes. 35

2. In a heat transfer apparatus of the character described, a plurality of parallel tubes, a header into which the tubes open, the header having a flow opening, the wall of the header through which the tubes project constituting a tube sheet, 40 a skirt secured to the tube sheet and surrounding the area of the sheet through which the tubes open, said skirt extending toward the flow opening, and a baffle plate disposed in said header between the flow opening and the skirt and extending across but in spaced relation to the extremity of the skirt, the plate having a marginal flange 45 surrounding and in spaced relation to the skirt and spaced from the adjacent walls of the header and extending toward the tube sheet to a point beyond the outer edge of said skirt whereby to equalize the flow through all of said tubes, said skirt being mounted upon the header for removal therewith. 50
